CLAIM

The ornamental design for a bone conductive audio headband according to my invention, as shown and described herein.

DESCRIPTION

FIG. 1 is a perspective view of the ornamental design for a first embodiment of a bone conductive audio headband according to my invention;

FIG. 2 is a side view of the ornamental design for the first embodiment of a bone conductive audio headband according to my invention;

FIG. 3 is an opposing side view of the ornamental design for the first embodiment of a bone conductive audio headband according to my invention;

FIG. 4 is a top view of the ornamental design for the first embodiment of a bone conductive audio headband according to my invention;

FIG. 5 is a bottom view of the ornamental design for the first embodiment of a bone conductive audio headband according to my invention;

FIG. 6 is a perspective view of the ornamental design for a second embodiment of a bone conductive audio headband according to my invention;

FIG. 7 is a side view of the ornamental design for the second embodiment of a bone conductive audio headband according to my invention;

FIG. 8 is an opposing side view of the ornamental design for the second embodiment of a bone conductive audio headband according to my invention;

FIG. 9 is a top view of the ornamental design for the second embodiment of a bone conductive audio headband according to my invention; and,

FIG. 10 is a bottom view of the ornamental design for the second embodiment of a bone conductive audio headband according to my invention.

The broken lines are illustrative of environmental structure only and form no part of the claimed design.
